CLAIM

The ornamental design for a triple header key holder, as shown and described.

DESCRIPTION

FIG. 1 is a front elevational view of a triple header key holder showing my new design;

FIG. 2 is a rear elevational view thereof;

FIG. 3 is a right side elevational view thereof, the left side being the mirror image thereof;

FIG. 4 is a top plan view thereof; and,

FIG. 5 is a bottom plan view thereof.

The broken line showing of key rings in FIG. 1 is for illustrative purposes and forms no part of the claimed design.

FIG. 1

FIG. 2

FIG. 3

FIG. 4

FIG. 5
